UNITED STATES PATENT OFFICE.

CHARLES A. SCHRANZ, OF PHILADELPHIA, PENNSYLVANIA, ASSIGNOR TO WALTER WOOD, TRADING AS R. D. WOOD & COMPANY, OF PHILADELPHIA, PENNSYLVANIA.

FEEDING DEVICE FOR GAS PRODUCERS.

Application filed November 4, 1921. Serial No. 512,790.

To all whom it may concern:

Be it known that I, CHARLES A. SCHRANZ, a citizen of the United States, residing in Philadelphia, Pennsylvania, have invented 55
certain Improvements in Feeding Devices 5
for Gas Producers, of which the following 60
is a specification.

The object of my invention is to improve 10
the construction of a device for feeding coal, 15
or other fuel, to gas producers so that the 20
fuel can be distributed evenly over the surface 25
of the fuel bed of the producer, or can 30
be directed towards the center or the outer 35
edge, or between the center and the outer 40
edge, as desired.

In the accompanying drawings:

Fig. 1 is a vertical sectional view through 45
the upper portion of a gas producer, illustrating 50
my improved feeding device mounted 55
on the top plate;

Fig. 2 is a plan view;

Fig. 3 is a sectional view on the line 60
3—3, Fig. 1; and

Fig. 4 is a side view illustrating the means 65
for adjusting the deflectors.

Referring to the drawings, 2 is the top 70
plate of a producer made in any suitable 75
manner. In the present instance the top 80
plate is fixed and the body portion rotates. 85
3 is the base on which the feeding device 90
is mounted and it has an opening 4 for the 95
passage of fuel into the interior of the producer. 100
5 is the feeding device having a cylindrical 105
casing 6. Extending through this 110
casing is a shaft 7 on which is a five-vaned 115
drum 8, which carries the coal from the 120
hopper 9 to the discharge spout 10, which is 125
directly above the opening 4 in the top plate 130
of the gas producer. On the shaft 7 is a 135
ratchet wheel 27, which is engaged by a 140
pawl 11^a on an arm 11. This arm is loosely 145
mounted on the extended hub of the ratchet 150
wheel 27, in the present instance. Attached 155
to a short arm 12, secured to the arm 11, is 160
a connecting rod 13, which is attached to 165
a pin 14 on a bevel gear wheel 15, which 170
meshes with a gear wheel 16 on a driven 175
shaft 17. The wheel 15 is mounted on a 180
shaft 18 and the two shafts 17 and 18 are 185
supported by a bearing 19.

Located in the lower portion of the feeding 190
device 5 are two horizontal shafts 20 and 21. The shaft 20 has a handle 22 and

the shaft 21 has a handle 23. On the shaft 20 is a deflector 24 and on the shaft 21 is 55
a deflector 25. The automatic coal feeder 60
is placed off center on the top plate of the 65
gas producer. When the deflectors are in the 70
position shown by dotted lines, Fig. 3, and, as 75
the body portion of the producer rotates, small 80
quantities of fuel are discharged onto the body 85
of fuel in a ring area equal to the width of the 90
drum, which width, however, is considerably 95
less than the radius of the producer.

In order to spread the fuel uniformly 100
over the interior radius of the fuel bed area, 105
the deflector plates 24 and 25 can be turned 110
by hand independently of each other to 115
the position shown in full lines, Fig. 3, 120
so as to deflect a portion of the stream 125
of fuel towards the center of the producer 130
and a portion towards the outer side of 135
the body of fuel in the producer. By this 140
construction, the fuel is evenly distributed 145
over the entire fuel bed.

I claim:

1. The combination in a gas producer, of 150
a rotating body portion; a fixed top plate 155
having a feed opening therein; a feeding 160
device for feeding material through the 165
opening in the top plate; and two horizontal 170
shafts, each having a handle and each 175
having a depending deflector so that, on 180
turning the shafts, the deflectors can be 185
adjusted in order to distribute the fuel over 190
the fuel bed of the producer as the body 195
portion rotates.

2. The combination in a gas producer, of 200
a rotating body portion; a fixed top plate 205
having a feed opening therein at one side 210
of the center of the producer; a feeding 215
device consisting of a water cooled casing 220
having a rotating vaned drum therein and 225
a hopper; means for intermittently rotat- 230
ing the drum, the casing having a discharge 235
passage above the feed opening in the top 240
plate; and two independent horizontal 245
shafts, each having manual operating means 250
and each having a flat faced deflector ex- 255
tending through the opening in the top 260
plate, the deflectors being so proportioned 265
that on adjusting the deflectors the fuel can 270
be distributed over the fuel bed of the pro- 275
ducer.

CHARLES A. SCHRANZ.
